The ornamental design for a control panel for a range, as shown and described.

DESCRIPTION

FIG. 1 is a front perspective view of a control panel for a range according to our new ornamental design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines represent environment or structure of the kitchen appliance and do not form any part of the claimed design.

Throughout the drawings, various views may not be provided, as the components in these views are unornamented or the ornamentation in these views is simply unclaimed.
